UNITED STATES PATENT OFFICE.

PHILIPP FISCHER, OF NEW YORK, N. Y.

IMPROVEMENT IN BUTTON-GAITERS.

Specification forming part of Letters Patent No. 179,779, dated July 11, 1876; application filed March 15, 1876.

To all whom it may concern:

Be it known that I, PHILIPP FISCHER, of New York, in the county and State of New York, have invented certain Improvements in Button-Gaiters, of which the following is a specification:

This invention relates to an improvement in that class of button-gaiters in which the quarter, the vamp, the leg, and the button-piece are all formed out of one and the same piece of leather or other material, and which have but a single seam. In such button-gaiters the patterns have been usually cut out, so that the portion to form the button-piece was situated on the same side with the portion to form the vamp, and in the finished gaiter the seam is situated on the same side with the button-piece—that is to say, on the outside of the gaiter. By this method of cutting out the patterns it is rendered difficult to shape or crimp the button-piece, and the seam in the finished gaiter extends over a tender portion of the foot, where it is liable to produce irritation.

My improvement consists in a button-gaiter made from one piece of leather or other material, and having its seam on the inside, while the button-piece is on the outside, whereby the appearance of the gaiter and its convenience for wear are materially improved.

In the drawing, Figure 1 represents an outside view of my gaiter. Fig. 2 is an inside view of the same. Fig. 3 is a plan of the pattern which I use for manufacturing my gaiters.

Similar letters of reference indicate corresponding parts in all the figures.

In this drawing, the letter A designates the pattern which I use in the manufacture of my

button-gaiter. In this pattern the part c is intended to form the vamp, the part b the leg, and the part a the button-piece. By referring to Fig. 3 of the drawing it will be seen that the button-piece a is situated on the side opposite to the vamp c, as shown by dotted lines, and consequently on one end of the pattern. By arranging the button-piece in this position I am enabled to cut the same so that it requires but very little crimping, and that, for the purpose of crimping, a small excess of material can be left to afford a hold for the crimping-tools; and, furthermore, when my gaiter is finished, the button-piece is situated on the outside, as shown in Fig. 1, while the seam d is situated on the inside, and extends over the soft hollow portion of the foot, where it is least liable to produce irritation.

By these means I am enabled to produce a neat and highly convenient button-gaiter with economy in labor.

What I claim, and desire to secure by Letters Patent, is—

As an improved article of manufacture, a button-gaiter, the quarter, the vamp, the leg, and the button-piece of which are made out of one piece, said button-piece being formed from that portion of the material opposite the vamp, so that the finished shoe has but a single seam, situated on the opposite side to that occupied by the button-piece, as shown and described.

In testimony that I claim the foregoing I have hereunto set my hand and seal this 10th day of March, 1876.

PHILIPP FISCHER. [L. S.]
